UNITED STATES PATENT OFFICE.

JOHN H. WILLIAMS, OF PASADENA, CALIFORNIA.

IRONING BOARD.

Application filed May 12, 1924. Serial No. 712,584.

This invention has to do with an ironing board, and has particular reference to a collapsible ironing board suitable for mounting in or on a wall, or the like.

It is an object of this invention to provide a collapsible ironing board of the character mentioned, which is effective and is simple and convenient to operate.

Another object of this invention is to provide an ironing board of the character specified, which is particularly compact when collapsed.

Another object of this invention is to provide an ironing board which is extremely simple and inexpensive of construction.

The various objects and features of this invention will be best and more fully understood from the following detailed description of a typical preferred embodiment thereof, throughout which description reference is had to the accompanying drawings in which

Fig. 1 is a vertical sectional view of the device provided by this invention showing it completely extended.

Fig. 2 is a front elevation of a portion of the parts shown in Fig. 1, being a view taken substantially as indicated by line 2—2 on Fig. 1.

Fig. 3 is a front elevation of the device showing it completely folded or collapsed.

Fig. 4 is a vertical sectional view showing the device completely folded or collapsed, being a view taken as indicated in line 4—4 on Fig. 3.

Fig. 5 is an enlarged detail sectional view taken as indicated by line 5—5 on Fig. 1 and

Fig. 6 is an enlarged detail sectional view taken as indicated by line 6—6 on Fig. 1.

The device of the present invention includes a frame in the form of a cabinet having a box like body 10 and a door 11 for the body. The body 10 in its preferred form is suitable for mounting in a wall, or the like, and includes vertical sides 12, horizontal ends 13 and a back 14. The body, in fact the entire frame or cabinet, can be advantageously constructed of wood, and is preferably made sufficiently large, particular as to height and thickness, to properly carry the parts hereinafter described.

The device includes two ironing boards; a main ironing board 15 for general use, and a sleeve ironing board 16 for small work or special use. The boards 15 and 16 may both

be formed of wood and may be of the usual size and design.

In accordance with this invention, the boards 15 and 16 are mounted in or related to the frame, in the following manner:

Two shafts 17 are rotatably carried by members 18 secured to the inner or forward side of the back 14 of the body of the frame. The two members 18 are mounted on the back 14 so that they are close to the sides 12, and so that they carry the shafts 17 in horizontal alignment. The arrangement and relation of the members 18 is clearly illustrated in Figures 1 and 2 of the drawings. Each shaft 17 has a long arm 19 extending from its outer end and a short arm 20 extending from its inner end. A rod 21 extends between and connects the outer ends of the long arms 19 and forms a support or carrier for the main board 15. The rod 21 is pivotally connected by means of a suitable strap or plate 22 with the main board 15 at a point substantially removed from the inner end of the board. The parts are preferably arranged so that the rod 21 extends under the board 15, and the plate 22, which may be formed of sheet metal, is secured to the under side of the board. The rod and plate operate to reinforce the board and prevent it from warping.

The inner end portion of the main board 15 is slidably pivotally connected with the cabinet or frame. In the particular form or construction illustrated in the drawings, the inner end portion of the main board 15 is slidably pivotally connected with the body of the cabinet through blocks 24 pivotally connected to either side of the board by pivot pins 25, and slidably carried in vertical guide ways or grooves 26 formed in the inner faces of the sides 12 of the body. Suitable means is provided for limiting or stopping upward movement of the inner end portion of the main board 15 in the body. In the preferred arrangement the members 18 which carry the shafts 17 extend downwardly from the shafts a considerable distance so that their lower ends 27 form stops for the inner end portion of the main board 15.

The short arms 20 extending from the inner ends of the shafts 17, are provided at their outer ends with inwardly turned parts 30 which form trunnions for supporting the sleeve board 16. The trunnions 30 may be connected with the board 16 in various man-

ners; it being found particularly simple and effective to extend them into sockets or openings 31 in opposite sides of the board 16 at a point somewhat removed from the inner end of the board. The trunnions 30 are rotatably carried in the sockets 31 so that the board 16 is pivotally mounted on the trunnions. Suitable stop means is provided for limiting upward movement of the inner end 10 of the board 16. This means may include a suitable stop part 33 mounted in the proper position on the front face of the back 14.

When the device is folded or collapsed, the arms 19 and 20 carrying the boards 15 and 16, respectively, are swung or folded as far as possible into the cabinet, and the two boards are folded up so that the sleeve board 16 lies comparatively close to the back 14 of the body, and the main board 15 lies closely 20 over the sleeve board 16. When the main board 15 is thus folded in, the inner end of the board is at the extreme lower end of the body, and the blocks 24 are at the lower ends of the grooves 26. To open the board for 25 operation the outer end of the main board 15 is swung out causing both the arms 19 and 20 to swing out and the lower end portion of the board 15 to move upwardly. When in this position the main board 15 reaches a horizontal position 30 its inner end engages the stops 27 which prevent further upward movement of the inner end of the board, and therefore prevent further downward movement of the outer end of the board. When in this position 35 the main board 15 is in condition for use. During opening or extension of the main board 15 the short arms 20 carrying the sleeve board swing outwardly from a position such as is shown in Fig. 4, to that 40 shown in Fig. 1.

During this outward movement of the short arms the sleeve board remains in an up position with its outer end against the back of the cabinet. When the short arms 45 20 are in the out position the inner end portion of the sleeve board is spaced from the back 14 so that the sleeve board will not accidentally fall and so that the sleeve board can be swung or lowered into operating position.

When it is desired to use the sleeve board, its outer end can be swung down until the board is in a horizontal position at which time its inner end will be in engagement with 55 the stop 33. The sleeve board can be moved into and out of operating position at any time while the main board is down. In Figs. 1 and 2 of the drawings I have illustrated both boards fully extended while in 60 Figs. 3 and 4 I have illustrated both boards completely folded in. When the main board is folded up the short arms are moved into the position shown in Fig. 4.

It is to be particularly noted that the construction provided by this invention involves

a very few parts, and is extremely simple both in construction and operation. The present construction permits of the boards being folded together in the cabinet in a particularly compact manner and has been 70 found to be particularly safe to operate in that the main board 15 will not come down to a horizontal position from the folded position unless deliberately operated.

In actual construction the shafts 17, the 75 arms 19 and 20, rod 21 and the trunnions 30 are formed of a single continuous piece of material. This feature is particularly noteworthy in that it eliminates numerous pivotal connections and joints ordinarily 80 found in devices of this kind, is extremely simple and inexpensive to manufacture, and makes a particularly neat, simple and strong construction. In practice the unit comprising the parts just mentioned is quickly and 85 cheaply formed, and greatly facilitates assembly of the device.

Having described only a typical preferred form of my invention I do not wish to limit myself to the specific details hereinabove set 90 forth but wish to reserve to myself any changes or variations that may appear to those skilled in the art or fall within the scope of the following claims.

Having described my invention, I claim: 95

1. In combination, a frame, a main board having its inner end slidably and pivotally connected with the frame, a horizontal shaft rotatably carried by the frame, a long arm extending from the shaft and pivotally connected with the main board at a point spaced from its inner end, a sleeve board, a short arm extending from the shaft and pivotally connected with the sleeve board at a point spaced from its inner end, and stop means 100 for the boards adapted to stop them when arranged horizontally, the arms being rigid with the shaft.

2. In a device of the character described, a frame, a main board connected with the frame, a sleeve board connected with the frame, two shafts rotatably carried in spaced relation and horizontal alignment by the frame, a long arm extending from the outer end of each shaft, a rod extending between the outer ends of the long arms to support the main board at a point spaced from its inner end, short arms extending from the inner ends of the shafts, the arms being rigid 11 with the shafts, means pivotally connecting the sleeve board with the outer ends of the short arms at a point spaced from the inner end of the board, and means for stopping the boards in a horizontal position.

3. A device of the character described including a frame having a vertical back and sides, vertical guideways in the sides of the frame, a main board, blocks pivotally connected with the inner end of the board and slidably carried in the guideways, a sleeve 12

board, two shafts, members connected with the back of the frame to rotatably carry the shafts in spaced relation and in alignment horizontally, said members being such that 5 their lower ends form stops to limit upward movement of the inner end of the main board, a long arm extending from the outer end of each shaft, a rod extending between the outer ends of the long arms, a plate 10 pivotally connecting the rod with the main board at a point spaced from its inner end, short arms extending from the inner ends of the shafts, trunnions on the outer ends of the short arms pivotally connected with 15 the sleeve board at a point spaced from the inner end of the board, and stop means for limiting pivotal movement of the sleeve board, the arms being rigid with the shafts.

4. In combination, a frame, a main board, 20 means connecting the main board with the frame engaging the board at a point spaced from its inner end so that the main board is movable between an extended position and

a position where it is folded against the frame, a sleeve board, means connecting the 25 sleeve board with the frame engaging the sleeve board at a point spaced from its inner end so that the sleeve board is movable between an extended position and a position where it is folded against the frame, and 30 an interconnection between said means whereby the inner end of the sleeve board is shifted with relation to the frame when the main board is operated.

5. A member for mounting two boards in 35 a frame including two coaxial shaft portions, long arms extending from the outer ends of the shaft portions, short arms extending from the inner ends of the shaft portions, a part extending between the outer 40 ends of the long arms, and trunnions extending from the outer ends of the short arms.

In witness that I claim the foregoing I have hereunto subscribed my name this 6th day of May, 1924.

JOHN H. WILLIAMS.
